CLAIM

The ornamental design for a support stand for an oscilloscope or similar article, as shown and described.

DESCRIPTION

FIG. 1 is a perspective view of support stand for an oscilloscope or similar article, showing our new design; FIG. 2 is a front elevation view thereof;

FIG. 3 is a top plan view of the stand;

FIG. 4 is a rear elevation thereof;

FIG. 5 is a bottom plan view of the stand; and

FIG. 6 is a side elevation view as seen from the left of FIG. 1.
